UNITED STATES PATENT OFFICE.

DALLAS BOUDEMAN, JR., OF KALAMAZOO, MICHIGAN.

PUMPING-ENGINE.

1,175,227.

Specification of Letters Patent. Patented Mar. 14, 1916.

Application filed July 20, 1914. Serial No. 851,975.

To all whom it may concern:

Be it known that I, DALLAS BOUDEMAN, Jr., a citizen of the United States, residing at Kalamazoo, Michigan, have invented certain new and useful Improvements in Pumping-Engines, of which the following is a specification.

This invention relates to improvements in pumping engines.

10 Further objects, and objects relating to structural details, will definitely appear from the detailed description to follow.

I accomplish the objects of my invention by the devices and means described in the 15 following specification.

The invention is clearly defined and pointed out in the claims.

A structure which is a preferred embodiment of my invention is clearly illustrated 20 in the accompanying drawing forming a part of this specification, in which:

Figure I is a perspective view of a structure embodying the features of my invention, the connecting rods being omitted.

25 Fig. II is a detail view, partially in vertical central section, of the structure shown in Fig. I in connection with a pump.

In the drawing similar reference numerals refer to similar parts in both views.

30 Referring to the drawing, 1 represents a pump of well known type. The engine 2 illustrated is of the two cycle type and as the details of the engine proper form no part of this invention they are not further 35 described herein. Any suitable engine or motor may be used.

The frame or base 3 is adapted for attachment to the floor, it being provided with bolt slots 4. At one end of the base is a 40 pedestal 5 having upwardly projecting arms 6 provided with shaft bearings 7. The upper end of the pedestal is forked to provide these arms. The clamp carrying arm 8 projects laterally from the arms 6 and is provided with an integral clamp member 9 and a removable clamp member 10, the removable clamp member being adjustably and 45 removable supported by the bolts 11. These clamp members are adapted to engage the column or body of the pump 1, as is shown in Fig. II. The engine 2 is provided with a base 12 which rests upon and is secured to the main base or frame 3 by the bolts 13. The crank shaft 14 is provided with a worm

gear 15 disposed between the arms of the 55 pedestal, the arms being curved outwardly at 16 to receive the worm.

The driven shaft 18 is arranged in the bearings 7 transversely above the crank shaft 14. On this driven shaft is a worm 60 gear 19 meshing with the worm 15, the worm gear 19 being arranged between the arms of the pedestal and supported laterally thereby. On the outer ends of the driven shaft 18 are arms 20 connected to the 65 pump rod 21 by the pitmen or connecting rods 22, the rods being connected to the crank arms 20 by the wrist pins 23. The arms 20 are provided with a series of wrist pin holes 24 so that the length of the stroke 70 of the pump may be regulated. This driving connection to the pump permits a small power motor being satisfactorily used.

The structure is simple and economical to produce and is very compact and may be 75 quickly applied to the pump in connection with which it is to be used.

I have illustrated and described my improvements in a simple and practical embodiment. I have not attempted to illustrate or describe various modifications which I contemplate as I believe the disclosure made will enable those skilled in the art to which my invention relates to embody or adapt the same as conditions may require. 80 I desire however, to be understood as claiming my improvements specifically in the form illustrated as well as broadly within the scope of the appended claims.

Having thus described my invention, 90 what I claim as new and desire to secure by Letters Patent, is:

1. The combination of a base having a forked pedestal at one end, the arms of the pedestal being provided with aligned shaft 95 bearings and with a laterally projecting arm provided with a pump clamp, an engine comprising a crank shaft provided with a driving worm mounted on said base at the side of said pedestal with its crank 100 shaft disposed longitudinally of the base and projecting between said pedestal arms, a driven shaft arranged in said pedestal bearings transversely above said crank shaft to project beyond said bearings, a 105 worm gear on said driving shaft meshing with said driving worm on said crank shaft, and crank arms on the ends of said driven

shaft adapted to swing at the sides of the pedestal and the sides of the pump to which said crank is secured.

2. The combination of a base having a forked pedestal at one end, the arms of the pedestal being provided with driven shaft bearings, an engine comprising a crank shaft provided with a driving worm mounted on said base at the side of said pedestal with its driving worm disposed between the arms of the pedestal, a driven shaft arranged in said bearings transversely above said worm, a worm gear disposed on

said driven shaft between said pedestal arms meshing with said driving worm on said 15 crank shaft, and driving connections mounted on said driven shaft at the outer side of said pedestal arms.

In witness whereof, I have hereunto set my hand and seal in the presence of two 20 witnesses.

DALLAS BOUDEMAN, JR. [L. S.]
